ABSTRACT OF THE DISCLOSURE

A chimney, particularly for land-based and maritime vehicles, of the type having a covering substantially the shape of an aircraft wing, which under the effect of the wind can determine a marginal whirlwind substantially parallel to the general direction of the relative flow of air around the device. These improvements have the effect of enhancing the formation of the marginal whirlwind starting at the upper end of the cover and in raising its trajectory to provide the use of a covering of reduced height and of a thickness which may attain 40% or more of its average length.

This invention relates to improvements for chimneys in order to evacuate fumes, and particularly to chimneys on land-based or maritime vehicles, such as steam locomotives, ships, etc., exposed to a relative wind, so as to prevent the dropping of fumes or smoke on the ship's deck. The present invention can also be used to evacuate fumes from industrial or residential buildings which are exposed to dominant winds of a substantially single direction.

The French Patent No. 925,303, issued to Jacques Valensi on July 12, 1927, for "Improvements in Chimneys, Particularly for Land-Based or Maritime Vehicles," provides for creating, in the vicinity of the end of the fume conduit or smoke stack of a steamer, a so-called marginal concentrated whirlwind, in the nucleus or center of which the fume was released. The fume thus was guided or directed to the outlet of the fume conduit like in a rigid pipe due to the sheath formed by the whirlwind.

According to a preferred embodiment of this invention the fume or smoke conduit was surrounded by a covering having the shape of an aircraft wing, preferably of trapezoidal appearance, and tapered at its end. This provides, under the effect of the relative wind at said end, a marginal whirlwind substantially parallel to the general direction of the relative flow of air around the device.

The examples described in the Valensi French patent were intended primarily for the evacuation of fumes from steamers or ships and applied more specifically to the case where one single fume conduit terminated at the top of the chimney of the steamer, exclusive of any other evacuation conduit for fumes, vapor or foul air.

These arrangements also required a certain number of precautions which will be enumerated below.

(1) The covering must be given sufficient height so that its upper end is placed slightly above the upper limit of the seaways of the ship superstructures located ahead of the chimney. Generally, this requirement led to a covering having a height at least equal to the length of its straight section at the base.

(2) The maximum thickness of the wing profile forming the straight section of this base should not exceed 30% of the length. The form of the covering then had to be frustoconical so that the thickness of the consecutive straight sections of the covering tapers off from the base to the top.

(3) To avoid the disintegration of the desired marginal whirlwind caused by an incidence of the relative

2

wind on the symmetry plan of the upper covering at an angle of about 25°, special devices, like baffle plates, blowing or suction slots were recommended.

The improvements according to the present invention relate to a certain number of arrangements usable alone or in combination and are applied to chimneys of the kind in question, enhancing the formation of the marginal whirlwind, and increasing or raising the trajectory of this whirlwind. These improvements are directed to aiding in preventing undesired dropping of the expelled fumes or smoke on to the ship's deck. Using the present invention it is possible to use a covering of very small height, whose profile may have a maximum thickness of 40% or more of the length of its base without destroying the desired marginal whirlwind at a very high incidence angle (in the order of 50°).

The first arrangement consists in providing, at the upper part of the covering of the chimney, a sealing surface with simple curvature. The sealing surface is provided with openings for the discharge of the fumes, vapors and foul air from the evacuation conduits, so that said covering has live ridges at its upper part.

According to a second arrangement of the invention, the discharge orifice from the principal conduit for the evacuation of the fumes bisects said surface at a simple curvature along a trapezoidal section whose center is arranged substantially at half the distance between the leading edge and the trailing edge of the curved profile forming the upper part of the covering.

According to a third arrangement of the invention the fume conduit from the auxiliary boilers or from the evacuation circuit of the foul air ends into an orifice placed ahead of this trapezoidal conduit, having rectangular shape, with the large base oriented parallel to the vertical symmetry plane of the steamer and the chimney. The conduit axis of the fume from the auxiliary boilers in the vicinity of the discharge being preferably vertical or slightly inclined to the vertical line.

According to a fourth arrangement of the invention the axis of the principal conduit of the fume in the vicinity of its discharge is about 35° against the horizontal line.

According to a fifth arrangement of the invention the orifices of the evacuation ducts of the vapors or gases are distributed on either side of said rectangular orifice.

The invention will be better understood from the following detailed description thereof taken in conjunction with the accompanying drawings in which:

FIGURE 1 of these drawings is an elevational view of a covering for a chimney according to the invention;

FIGURE 2 is a profile view of the covering shown in FIGURE 1;

And FIGURE 3 is a plan view of this same covering.

FIGURE 1 shows a view in elevation of a covering for a chimney of a steamer or ship provided with the improvements according to the invention. It is to be understood that the present invention can be readily adapted to other environments as mentioned previously, and that this disclosure is merely for illustration of the invention. As the description continues, reference will be made to FIGURES 2 and 3, where the same reference symbols have been used.

FIGURE 1 shows schematically by a horizontal broken line the upper deck of the ship at the site normally provided for the principal chimney for the evacuation of the fumes.

On this line reference numeral 1 identifies the front side of the ship, and reference numeral 2 the rear. The side wall 3 of the covering is frustoconical in shape, and the covering includes a base 4 as shown in FIGURE 3.

According to the invention the upper part of the covering is provided with a simply curved sealing surface 5,

formed by a portion of a cylindrical surface, whose generatrices are perpendicular to the symmetry plane of the covering and bear down on a curve having a substantially parabolic appearance as is shown most clearly in FIGURES 2 and 3.

FIGURE 3 shows the different orifices for evacuating the fumes, vapor and foul air, placed into surface 5. The principal orifice 6 for the evacuation of the fumes is, according to the invention, of trapezoidal shape. FIGURE 1 shows that the axis 7 of conduit 8 (in dashed lines) terminating at this orifice forms an angle substantially equal to 35° with the horizontal line.

With regard to the arrangement of orifice 6 on the surface 5 it is shown that the center of the trapezoid is substantially at half way or midway between the leading edge 9 and the trailing edge 10 of the curved profile forming surface 5. The discharge orifice 11 of the gases from the auxiliary motors is shown in FIGURE 3. This orifice has a rectangular shape whose longest side is oriented parallel to the vertical symmetry plane of the ship and the chimney. FIGURE 1 shows that the axis 12 of the conduit terminating at orifice 11 is slightly tilted against the vertical line. However, it could also be made vertical if desired.

Referring to FIGURE 3, the evacuation orifices 13, 14, 15 and 16 of the vapors or gases are shown as distributed on either side of the rectangular orifice 11. The conduits terminating at these orifices have a substantially vertical axle similar to the rectangular orifice 11.

Under these conditions and due to the configuration just described, a gaseous vertical vein of relatively small thickness which escapes upstream from the principal fume conduit 8 produces at its downward flow a depression enhancing the discharge of the fumes and raising the marginal whirlwind axis 7.

Furthermore, this escape of a gaseous vein modifies the distribution of the pressures along the profiles of the covering in the vicinity of the upper end, resulting in increasing at equal incidence the intensity of the marginal whirlwind and preventing its destruction at very great incidence angles.

It then is possible in accordance with this invention to reduce the height of the chimney by making it approximately half the profile line at the base of the covering and increasing its relative thickness, without observing any lowering of fumes on the deck. Thus, these improvements have the effect of enhancing the formation of the marginal whirlwind starting at the upper end of the cover and in raising its trajectory to provide the use of a covering of reduced height and of a thickness which may attain 40% or more of its average length.

FIGURES 1 and 2 shows a certain number of parameters L , l E and H , determining the principal dimensions of the covering. L and l respectively designate the length of the covering at its base and upper part; E and e designate the corresponding thicknesses at the base and upper part; and H the height. In an embodiment of evidently non-limitative nature, and presented here merely as an example of the invention, the relations between the different parameters are as follows: $E/L=0.3$; $e/l=0.40$; $H/L=0.56$.

The foregoing detailed description has been given for clearness of understanding only, and no unnecessary limitations should be understood therefrom, as modifications will be obvious to those skilled in the art.

What is claimed is:

1. An improved covering for chimneys of moving vehicles, such as ships and the like, including a chimney

having at least one fume conduit with a discharge end for discharging fumes from said chimney, the improved covering comprising:

5 a frusto-conical shaped side wall surrounding said conduit and extending upwardly towards said discharge end; said side wall terminated in a curved sealing surface having apertures therein aligned with the discharge end of said fume conduit for discharging the fumes from the chimney through said sealing surface; said discharge end of said fume conduit bisecting said curved sealing surface along a trapezoidally shaped section, the center of said section being substantially midway between the respective leading and trailing edges of said curved sealing surface; and said curved sealing surface formed by a portion of a cylindrical surface, whose generatrices are perpendicular to the symmetry plane of the covering and provide a substantially parabolic termination of the frusto-conical side wall and the curved sealing surface in a plan view of said covering, for enhancing the formation of a marginal whirlwind at said discharge end, thereby increasing the discharge angle of said fumes from the chimney towards the vertical axis of said chimney to prevent undesired dropping of the fumes onto the ship.

2. The improvement of claim 1, including at least a second fume discharge conduit having a discharge end aligned with a corresponding aperture in said curved sealing surface, said second fume discharge end intermediate the leading edge of said sealing surface and said first mentioned discharge end, said second fume discharge end having a rectangular shape with the longest sides of said rectangle parallel to the vertical symmetry plane of said chimney, and wherein the longitudinal axis of said second fume discharge end is substantially vertical.

3. The improvement of claim 1, including an auxiliary boiler conduit having a boiler discharge end aligned with a corresponding aperture in said curved sealing surface, said boiler discharge end intermediate the leading edge of said sealing surface and said first mentioned discharge end, said boiler discharge end having a rectangular shape with the longest sides of said rectangle parallel to the vertical symmetry plane of said chimney, and wherein the longitudinal axis of said boiler discharge end is substantially vertical.

4. The improvement of claim 3, including a series of vapor discharge conduits having respective discharge ends on either side of the rectangularly shaped auxiliary boiler discharge end.
